DESIGN FOR AN ELECTRIC FACIAL MASK

Simon Dansk, Santa Monica, Calif.

Application December 7, 1938, Serial No. 81,629

Term of patent 14 years

To all whom it may concern:

Be it known that I, Simon Dansk, a citizen of the United States, residing at Santa Monica, in the county of Los Angeles and State of California, have invented a new, original, and ornamental Design for an Electric Facial Mask, of which the following is a specification, reference being had to the accompanying drawing, forming a part thereof.

Figure 1 is a perspective view of an electric facial mask showing my new design, and taken from a position to one side and rearwardly thereof.

Fig. 2 is a front elevational view thereof.

Fig. 3 is a side elevational view thereof.

I claim:

The ornamental design for an electric facial mask, as shown.

SIMON DANSK.
